TWIN FRONT CAR MAT

William C. Gerber, Wooster, Ohio, assignor to
Rubbermaid Incorporated, Wooster, Ohio

Filed Nov. 13, 1972, Ser. No. 306,374

Term of patent 14 years

Int. Cl. D6—11

U.S. Cl. D12—203

FIG. 1

FIG. 2

FIG. 3

FIG. 1 is a top plan view of a twin front car mat embodying my new design.

FIG. 2 is a top plan view of a twin front car mat showing a second embodiment of my new design.

FIG. 3 is an enlarged fragmentary top plan view of the area indicated in FIG. 2.

FIG. 4 is an enlarged fragmentary sectional view thereof taken on line 4—4 of FIG. 1.

FIG. 5 is an enlarged fragmentary sectional view thereof taken on line 5—5 of FIG. 1.

FIG. 6 is a greatly enlarged fragmentary sectional view thereof taken on line 6—6 of FIG. 2.

The undisclosed bottom is substantially flat and unornamented.

I claim:

The ornamental design for a twin front car mat, as shown and described.
